UNITED STATES PATENT OFFICE.

WILLIAM C. VANNEMAN, OF ANDERSON, INDIANA.

TOY.

1,252,515.

Specification of Letters Patent.

Patented Jan. 8, 1918.

Application filed June 16, 1917. Serial No. 175,090.

To all whom it may concern:
Be it known that I, WILLIAM C. VANNEMAN, a citizen of the United States, and a resident of Anderson, county of Marion, and 5 State of Indiana, have invented a certain new and useful Toy; and I do hereby declare that the following is a full, clear, and exact description thereof, reference being had to the accompanying drawings, in which like 10 letters refer to like parts.

My invention relates to new and useful improvements in toys and primarily a toy formed in the shape of a pistol.

My object is to provide a toy of this class 15 for catapulting disks of card board or similar material whereby the card board will be caused to sail through the air.

A further object is to so construct the device that the operation thereof for throwing 20 the disk will be similar to the action of a pistol in firing the same.

A further object is to so construct the parts of the toy that it can be very cheaply manufactured and at the same time rendered strong and durable.

The full nature of the invention will be understood from the accompanying drawings and the following description and claims.

30 Figure 1 is a perspective view of the toy showing a disk mounted thereon in dotted lines. Fig. 2 is a top plan view thereof. Fig. 3 is an elevation partly in section showing the disk in position to be cast therefrom. Fig. 4 is a detail perspective view of the 35 operating trigger.

Referring to the drawing 1 indicates the body or grip portion of the toy or pistol and 40 2 indicates an extension or barrel portion integral therewith and it will be clearly understood that said grip portion and extension may be formed in any suitable shape or design or of any preferred material.

The extension 2 is provided with a central 45 longitudinally extending slot 3 in which is mounted a catapulting or throwing spring 4, said spring being substantially V-shaped in general outline, the apex 5 thereof being bent around a stud 6 while one arm of the 50 spring is preferably bent around a stop 7 adjacent the outer end of the slot and the opposite arm thereof provided with a substantially L-shaped extension 8.

The vertical arm 9 of the extension 55 projects above the upper edge of the extension 2 and is adapted to project through an open-

ing 10 in a retaining tongue 11, said retaining tongue being flat and preferably of spring metal and having its outer end fixed to the grip portion 1 while its inner end is 60 slightly upwardly curved so that a disk 12 may be readily introduced thereunder. The arm of the spring 4 having the extension 8 thereon is operated to cause the arm 9 to strike the edge of the disk 12 a blow sufficient to cause the disk to sail through the air, by means of the trigger 13 which is pivoted at 14 in the slot 3, the upper end 15 of the trigger being curved forwardly so that the end of the curved portion will engage the 70 arm of the spring 4 having the extension 75 thereon. If desired the end of the trigger may be provided with a recess 16 for the reception of the arm of the spring 4, thus holding said arm in proper alinement with the trigger at all times.

In operation the toy is grasped in the hand similar to a pistol and a disk 12 then introduced beneath the free end of the retaining tongue 11 and in the path of the 80 vertical arm 9 of the extension 8 so that when the lower end of the trigger 13 is drawn rearwardly by the pressure of the finger thereon the arm of the spring 4, engaged by the upper end of the trigger, will 85 be moved forwardly. This action will bring the arm 9 of the extension 8 against the wall of the opening 10 so that the continued movement of the trigger 13 will increase the tension on the arm of the spring 4 to 90 such an extent that when the arm 9 is released from the opening 10, it will deliver a sudden and strong blow against the edge of the disk thus catapulting the disk forwardly and causing the same to sail through the 95 air. Pressure is then released from the lower end of the trigger whereupon the natural spring tendency of the spring 4 will return the extension 8 to its initial position 100 and again engage the vertical arm 9 with the opening 10, when another disk may be applied and the above operation repeated. In order to obtain the best results in the sailing of the disk, it is so introduced beneath the tongue 11 that the arm 9 will engage the disk nearer to one end thereof than to the other, thus imparting a better whirling motion to the disk, though it will be understood that any form or shape of disk may be used and satisfactory results obtained.

The invention claimed is:

1. A toy, comprising a grip portion and

an extension, said extension having a longitudinal slot, a retaining member attached to said grip portion and extending over a portion of said slot, a spring member in said slot normally in engagement with said retaining member and a trigger pivoted in said slot adapted to tense said spring member and release the same from the retaining member for catapulting an object from the extension, said spring member being arranged to automatically reengage said retaining member when pressure is removed from the trigger.

2. A toy, comprising a grip portion having an integral extension, said extension having a slot, a retaining tongue attached to the upper edge of the grip portion, said tongue having an opening adjacent its free end, a spring member mounted in said slot having one of its ends normally projecting through said opening and means to tense parts of the spring member and release the end thereof from said opening whereby a disk introduced beneath the free end of the tongue will be catapulted therefrom.

3. A toy, comprising a body portion having an integral extension in which is formed a slot, a spring member having one of its ends fixed in said slot and its opposite end

provided with an L-shaped extension, a retaining tongue fixed at one end to said body and provided with an opening adjacent its opposite end, the free end of the L-shaped extension being adapted to project through said opening, and means to tense the spring member and release the extension from said opening whereby an object forwardly of the extension will be catapulted through the air.

4. A toy, comprising a body portion having an integral extension in which is formed a slot, a substantially V-shaped spring positioned in said slot and having one of its ends fixed within the slot, the opposite end provided with an extension, a retaining tongue fixed to the body portion and having an opening adjacent one end for the reception of the free end of the extension, a trigger pivoted in said slot and having a recess for engagement with one section of said spring whereby when the free end of said trigger is moved rearwardly the portion of the spring engaged by the trigger will be tensed and an object catapulted forwardly when the end of the extension is released from the opening in the tongue.

In witness whereof, I have hereunto affixed my signature.

WILLIAM C. VANNEMAN.
